MULTIPLE COMPARTMENT VENDING MACHINE

William D. Young and William Andrew Harris, Greenville, S. C., assignors, by direct and mesne assignments, of twenty per cent to William D. Young, twenty per cent to Dorothy R. Young, twenty per cent to Betty Jane Young, twenty per cent to Jean Ann Young, and twenty per cent to Nancy Lou Young, all of Greenville, S. C.

Application August 14, 1944, Serial No. 549,432

5 Claims. (Cl. 312—48)

1

This invention relates to a vending machine and more especially to a vending machine adapted to support two rows of merchandise in side by side relation with vending mechanism operating alternately to dispense an article of merchandise first from one row and then from the other, said vending mechanism being controlled and operated entirely by means of a coin or check deposited in the apparatus together with the weight of the column of merchandise supported by the vending mechanism.

It is an object of this invention to provide a vending machine comprising a movable dispensing vending member adapted to support two columns of merchandise with means for operating the dispensing mechanism to deliver the lowermost one of an article of merchandise from a column of merchandise, and then on a subsequent operation to deliver the lowermost article of the other column of merchandise.

It is another object of this invention to provide a vending machine having an oscillatable member adapted to support two columns of merchandise in parallel relation with means for operating the dispensing mechanism so as to deliver a lowermost article from one column of merchandise upon one operation and to deliver the lowermost article of merchandise from the other column upon the next operation, said operations continuing in alternating sequence until the columns of merchandise are exhausted.

It is another object of this invention to provide a vending machine having means for supporting a plurality of columns of merchandise with oscillatable means adapted to support the columns of merchandise and coin controlled means for controlling the oscillatable means and the oscillatable means controlling each other so as to deliver the lowermost article from one column of merchandise upon one operation of the machine, and to deliver the lowermost article of merchandise from the other column upon the next operation of the machine.

Some of the objects of the invention having been stated, other objects will appear as the description proceeds, when taken in connection with the accompanying drawings, in which—

Figure 1 is an isometric view on a reduced scale of the vending machine;

Figure 2 is a front elevation of the machine with the front cover removed;

Figure 3 is a vertical sectional view taken along the line 3—3 in Figure 2, and showing the cover in position, and omitting all articles of merchandise except the lowermost or delivered one;

2

Figure 4 is a vertical sectional view similar to the upper portion of Figure 3, but showing the parts in a different position;

Figure 5 is a front elevation of the central portion of Figure 2, but showing the parts in a different position;

Figure 6 is a view similar to Figure 5, but showing the parts in a different position;

Figure 7 is a vertical sectional view taken substantially along the line 7—7 in Figure 3;

Figure 7A is a vertical sectional view taken along the line 7A—7A in Figure 2.

Referring more specifically to the drawings, the numeral 10 indicates the casing of the vending machine proper which comprises a back wall 11, side walls 12 and 13, top wall 14, bottom 15, and a removable front 16. On the inner surface of front portion 16, there is secured a plurality of downwardly depending clips 17 which fit on the inside of upturned flange 18 extending upwardly from the front edge of the bottom member 15 and these clips 17 hold the lower portion of the front member against removal, and when the top portion is slid over the upper end of the casing, a sheet metal tongue 19 having a slot 20 therethrough will slip over a hasp 21 and a suitable lock may be placed through this hasp 21 for locking the cover 16 in position.

Cover 16 has a slot 22 through which a coin or check may be inserted, and has a pair of windows 23 and 24 through which the lowermost articles of merchandise in the machine may be observed. It has an opening 25 through which the articles of merchandise 26 are delivered one at a time. These articles 26 fall downwardly, when delivered, onto a sloping portion 27, and an upturned ledge 28 prevents the article of merchandise from sliding entirely out of the machine, but it is within reach of the operator.

When a coin or check 29 is inserted through the opening 22, it enters a passageway or channel 30 which slopes downwardly to allow the coin to roll of its own weight and it passes into a vertical portion 31 of the coin chute. This coin chute has a slot 32 into which a weak leaf spring 33 projects.

On the side of the chute 31 opposed to the opening 32 is a larger opening 34 through which the weak leaf spring 33 projects, and if a light coin or check is dropped into the chute, it will be deflected outwardly through the opening 34 and will fall onto a sloping portion 35 where it will roll out of the machine through an opening 36. If the coin is of sufficient weight, the spring 33 will be bent backwardly so as to not interfere

with the downward falling of the coin or check, and the coin will fall downwardly below the openings 32 and 34, and will strike the free end of a lever 40 which projects through an opening in the side of the channel or guide 31, and will move this lever on its pivot 41.

Two compartments 44 and 45 for housing the articles of merchandise 26 are separated from each other by means of vertical partition members 47 and 48. A sheet or plate member 49 is supported by having end angles fitting against the plate 47 at its upper end and onto an angular portion 50 near the bottom of member 47. This plate 49 has secured thereto and in spaced relation thereto a plate member 51 and the pivot pin 41 projects through the plate members 51 and 49 to pivotally support the lever 40.

Suitable stops 54 and 55 are secured on the plate member 49 for limiting the swinging movement of lever 40. Lugs at the lower ends of members 47 and 48 are passed through a slot in a supporting member 56 and are turned outwardly as clearly shown in Figure 2 as at 57 and 58. Member 56 is spot welded or soldered to the interior surface of side wall 13.

Supported in the rear wall 11 and the member 56 is a shaft 60 having notched members 61 and 62 thereon for supporting simultaneously the columns of merchandise disposed in compartments 44 and 45. These notched members 61 and 62 have small portions 61a and 62a and larger portions 61b and 62b. This shaft 60 has also fixed thereon a quadrant 63 having a pair of notches 64 and 65 therein and a lever 66 having a tongue 67 on its lower edge is pivoted as at 68 and at its free end is connected to a wire 70 which is led upwardly and connected to lug 71 on lever 40.

Sloping members 73 and 74 are fixed in the machine and have ears 75 and 76 which are projected through the lower portion of frame member 56 so as to direct the falling articles of merchandise centrally of the apparatus to where they will fall onto the sloping portion 27 to slide downwardly to rest against the projection 28.

The interior surfaces of side walls 12 and 13 have projecting portions 78 and 79 thereon for directing the articles of merchandise inwardly towards each other to rest on the dispensing members 61 and 62.

Although the coin box 37 is shown on the back of the machine, it is evident that by making the machine higher in vertical length that suitable means can be incorporated within the casing for the coin box, but since the coin box is not a part of the invention, the machine has been shortened in order to show the parts on a larger scale. The coin 29 passes from chute 31 through opening 38 in the back wall 11 into the coin box 37.

The operation of the mechanism is as follows: When a coin or check 29 is pushed through the opening 22, it rolls downwardly in portion 30 of the coin chute and into vertical portion 31 and being of sufficient weight moves spring 33 out of its way and falls downwardly to engage the right-hand end of lever 40 in Figures 3 and 4, and will swing the lever 40 on its pivot 41 which will raise lug 71 and through the pull of wire 70 will move the pivoted lever 66 upwardly from the position shown in Figure 2 to the position shown in Figure 5 which will allow the weight of the column of merchandise on the portions 61b and 62b on the right-hand side of the machine to oscillate the shaft 60 in a clockwise manner and will allow the parts to be moved to the position shown in Figure 6, which will free the lowermost article of

merchandise in the right-hand column and allow it to fall to the position shown in Figure 3, and the right-hand column will then be supported by small portions 61a and 62a while larger portions 61b and 62b will move beneath and support the left-hand column. At the same time, the dog 67 will fall into cavity 64 and lock the mechanism in position until another coin is inserted into the opening 22, at which time the above-described operation is repeated, except that the lever 66 being raised, will allow the shaft 60 to oscillate in a counter-clockwise manner and will move the parts back to the position shown in Figure 2, and the lowermost article of merchandise in the left-hand column will fall downwardly out of its associated notches in the members 61 and 62 into the trough whose bottom is indicated at 27.

In the drawings and specification, there has been set forth a preferred embodiment of the invention, and although specific terms are employed, they are used in a generic and descriptive sense only, and not for the purpose of limitation, the scope of the invention being defined in the claims.

We claim:

1. In a vending machine comprising a casing having a pair of vertically disposed compartments in which articles to be vended may be stored, an oscillatable supporting member disposed between and at the lower ends of said compartments for supporting columns of merchandise in said compartments and being movable by the weight of articles disposed thereabove, the supporting means having upper and lower projections thereon, the lower projections having a longer radius than the upper projections so that when swung, the lower projections will allow the lowermost article of one compartment to pass out of the machine and the upper projections will engage the next article thereabove and prevent its moving out of the machine, and will also release the lowermost article in the next compartment and allow it to move downwardly a predetermined distance, and the lower projections will engage the lowermost article in the next compartment and prevent its completely passing out of the machine, releasable locking means for holding the oscillatable member in a fixed supporting position against the weight of the articles disposed thereabove, means for releasing the locking means for the oscillatable member to allow the oscillatable member to be swung by the weight of the articles in one compartment resting on the lower projections to allow the lowermost article in one compartment to pass from one of the columns of merchandise and to release the lowermost article in the next compartment, but to engage it before it has passed entirely out of its compartment.

2. In a vending machine comprising a casing having a pair of vertically disposed compartments in which articles to be vended are adapted to be stored, supporting means at the lower end of the compartments for supporting articles of merchandise, said supporting means having opposed upper and lower projections thereon, said lower projections being of a greater radius than the upper projections and being oscillatable to allow the lower projections to release the lowermost article of merchandise to pass out of the machine and to move the upper projection under the next article and prevent its downward movement in its compartment, said lower projections when releasing an article in one compartment swing to a

position below the other compartment to support the lowermost article therein, releasable locking means for holding the supporting means against oscillation, means for releasing the locking means from the supporting means and allowing same to swing under the weight of the articles in one compartment resting on the longer lower projections, to release the lowermost article in one compartment to pass out of the machine and to engage the next article thereabove and prevent further downward movement of the articles.

3. In a vending machine, a pair of side by side compartments for holding a plurality of articles to be vended, said machine having a delivery opening, oscillatable means having upper and lower radially projecting supports for supporting the articles against downward movement in the compartments, the lower supports having a greater radius than the upper supports, said oscillatable means being swingable by the weight of the articles resting on the lower supports, releasable locking means for preventing movement of the oscillatable means under the weight of the article supported by the lower supports, means for moving the locking means to allow the lower supports to move from beneath one column of articles and to a position beneath the other column of articles and to position the upper support beneath the column from whence an article has been released to thus allow the lowermost article in the first column to pass through the delivery opening.

4. In a vending machine having a casing provided with a pair of side by side compartments for holding articles of merchandise, an oscillatable member disposed adjacent the lower ends of the compartments and having an upper supporting surface and two lower supporting surfaces, each having a longer radius than the radius of the upper supporting surfaces for supporting a column of merchandise in each compartment, the weight of one column of merchandise resting on one of the lower supporting surfaces acting to move the oscillatable member to allow the lowermost article in one column supported by the first of the lower supporting surfaces to pass out of the machine while the upper supporting surface arrests downward movement of the next article thereabove, and the second lower supporting surface prevents downward movement of all of the articles in the adjacent compartment, means on the oscillatable member having two notches therein, and a dog adapted to rest by gravity in one of these notches to prevent movement of the oscillatable member, means for releasing the dog from one of the notches to allow the weight of one column of articles to move the oscillatable mem-

ber until the dog falls in the other notch, thus allowing the oscillatable member to swing to allow one of its lower supporting surfaces to swing from beneath one column of merchandise to allow the lowermost article in said column to pass out of the machine, and at the same time, allowing the upper supporting surface to swing beneath the next article thereabove and prevent the next article thereabove in that column from passing out of the machine, the second lower supporting surface also swinging beneath the lowermost article in the adjacent column and preventing all of the articles in the adjacent column from passing out of the machine.

5. In a vending machine having two vertically disposed compartments disposed in side by side relation for holding two columns of articles, oscillatable means disposed below both columns and having upwardly projecting portions and downwardly projecting portions, the downwardly projecting portions serving to support an article about to be dispensed and the upwardly projecting portions supporting the next succeeding article to be dispensed, the downwardly projecting portions each having a longer radius than the upwardly projecting portions, the weight of one of the columns of articles resting on the downwardly projecting portions tending to oscillate the oscillatable means to allow the article resting on the downwardly projecting portions to deliver the last-named article to the exterior of the machine, said oscillatable means having an arm extending therefrom and having a pair of spaced cavities therein, a detent normally urged to occupy one of the cavities to prevent oscillation of the oscillatable means, coin controlled means for releasing the detent from a cavity to allow the article ready to be dispensed to move to the exterior of the machine and thus allow the lowermost article in the other compartment to move onto the downwardly projecting portions.

WILLIAM D. YOUNG.
